UNITED STATES PATENT OFFICE

122,968

DESIGN FOR A DRAWN FURNACE RADIATOR

Cleo Harris, Kalamazoo, Mich., assignor to Borg-Warner Corporation, Chicago, Ill., a corporation of Illinois

Application March 9, 1939, Serial No. 83,463

Term of patent 14 years

To all whom it may concern:

Be it known that I, Cleo Harris, a citizen of the United States and resident of the city of Kalamazoo, in the county of Kalamazoo and State of Michigan, have invented a new, original, and ornamental Design for a Drawn Furnace Radiator, of which the following is a specification, reference being had to the accompanying drawing, forming part thereof, wherein:

Fig. 1 is a perspective view of the drawn furnace radiator showing my new design;

Fig. 2 is a rear elevational view of the radiator shown in Fig. 1; and

Fig. 3 is a plan view of the radiator shown in Fig. 1.

I claim:

The ornamental design for a drawn furnace radiator, substantially as shown.

CLEO HARRIS.
